UNITED STATES PATENT OFFICE.

IGNATIUS MAISANO, OF WILMINGTON, DELAWARE.

TOY.

1,356,647.

Specification of Letters Patent. Patented Oct. 26, 1920.

Application filed February 26, 1920. Serial No. 361,571.

To all whom it may concern:

Be it known that I, IGNATIUS MAISANO, a citizen of the United States, residing at Wilmington, in the county of New Castle 5 and State of Delaware, have invented new and useful Improvements in Toys, of which the following is a specification.

This invention relates to a trundling toy which may be drawn or pushed over the 10 floor or ground, such movement causing a wheel-like frame to rotate in a vertical plane and ring a bell, or a plurality of bells, and at the same time cause figures carried by the wheel and revolving therewith to 15 swing to and fro and perform entertaining tumbling and gymnastic tricks.

The invention consists in the novel combination and arrangement of parts herein- 20 after described and claimed, and shown in the accompanying drawing in which—

Figure 1 is a side elevation of my im- 25 proved toy, and Fig. 2 a rear elevation of the same.

10 indicates a platform to the underside of which are secured bearings 11 supporting a cross shaft or axle 12. The ends of the shaft 12 project beyond the sides of the platform 10 and carry wheels 13 fixed thereon, the travel of said wheels over the 30 floor or ground causing the shaft to turn. The shaft 12 carries a drum 23 the purpose of which is described later. At the forward end of the platform 10 is a handle 14 by means of which the toy may be pulled or 35 pushed.

Two supports 15, spaced apart, rise vertically from the platform 10 and are connected near their tops by a cross rod 16. The supports 15, shown as towers or bel- 40 fries, are given ornamental outlines. Each support 15 has a vertically elongated opening 9 formed therein a suitable distance above the platform 10 to receive the end of a transverse axle 17 upon which is mounted 45 a relatively large frame or wheel 18 rotatable between said supports. The wheel 18 consists of two spaced disks 19 secured on the opposite ends of the hub 20 carried by the axle 17, the disks being connected further by a plurality of rods 21 extending 50 between them near their peripheries. The wheel 18 normally rests upon the drum 23

by reason of the coöperation of the elongated openings 9 with the transverse axle 17. Pivottally suspended figures or automata 55 22 are hung on the rods or trapeze bars 21 so as to move freely thereon and swing to and fro or assume different positions as the wheel 18 revolves due to its gravital contact with the drum 23. The wheel 18 rotates 60 freely irrespective of the mode of propulsion whether backward or forward.

A bell 24 is suspended from the rod 16 the latter connecting with the tops of the supports 15, the bell having a swinging clapper 65 25 adapted to be struck by the rods or trapeze bars 21 as they pass the bell. Two or more bells may be used, as also bells of varied type and tone. Flags 26 are or may be displayed on shafts projecting from 70 different parts of the supports 15, thus adding to the amusing and educational character of the toy.

The several parts entering into the structure described may be of wood or metal, or 75 a combination of the two substances.

I claim:—

1. A toy comprising a platform mounted on wheels fixed to an axle and adapted to be drawn or pushed along the floor or ground, 80 supports fixed to said platform, a relatively large wheel between said supports journaled in vertical slots in the latter, rods or trapeze bars carried by said wheel, figures hung from said rods or bars and free to swing or 85 turn over thereon, a bell mounted on said supports, a swinging clapper for said bell adapted to be struck by said rods during the rotation of said wheel, and a drum fixed on said axle upon which the relatively large 90 wheel rests and by which it acquires rotation.

2. A toy comprising a platform supported on wheels fixed to an axle and adapted to be drawn or pushed along the 95 floor or ground, a drum rigid with said axle, a pair of supports mounted on the platform and spaced apart, each support having a vertically elongated opening therein, a relatively large wheel rotatable 100 between said supports and journaled in said elongated openings to allow the wheel to rest upon said drum and to be rotated thereby, said wheel comprising spaced disks,

a hub and transverse rods or trapeze bars, a bell mounted on the supports and adapted to be sounded by periodic contact with said rods, and figures depending from said rods or trapeze bars and adapted to exhibit tumbling or other gymnastic feats as the toy is pushed or pulled.

In testimony whereof I affix my signature in presence of two witnesses.

IGNATIUS MAISANO.
